(57) **CLAIM**

The ornamental design for an earphones, as shown and described.

DESCRIPTION

FIG. 1 is a perspective view of an earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the earphones where the earphones are received in a charging case.

The broken lines in FIG. 9 showing the charging case depict environment and form no part of the claimed design. The other broken lines in the drawings depict portions of the earphones that form no part of the claimed design.

1 Claim, 9 Drawing Sheets
